MULTI-PURPOSE FUNERAL CAR

Willard C. Hess and Charles W. Hartline, Cincinnati,
Ohio, assignors to Hess and Eisenhardt Manufacturing
Company, Rossmoyne, Ohio, a corporation of Ohio

Application January 17, 1958, Serial No. 49,286

Term of patent 14 years

(Cl. D14—17)

Figure 1 is a perspective view of a multi-purpose funeral car showing our new design. In this figure the convertible top is shown in the up position.

Figure 2 is a perspective view similar to Figure 1 in which the convertible top is shown in the down or open position.

The side of the funeral car not shown is the same as the side shown. The dominant features of our new design reside in those portions shown in full lines.

We claim:

The ornamental design for a multi-purpose funeral car, substantially as shown and described.
